(57) **CLAIM**

The ornamental design for an elevated animal feeding bowl, as shown and described.

DESCRIPTION

FIG. 1 is a top perspective view of the elevated animal feeding bowl of the instant invention;

FIG. 2 is a bottom perspective view thereof;

FIG. 3 is a front view, the rear view being a mirror image thereof;

FIG. 4 is a right side view, the left side view being a mirror image thereof;

FIG. 5 is an enlarged top view thereof;

FIG. 6 is an enlarged bottom view thereof, illustrating the riser legs in a stored position;

FIG. 7 is a bottom perspective view thereof illustrating the riser legs in an assembled position;

FIG. 8 is a top perspective view illustrating the riser legs in an assembled position;

FIG. 9 is an enlarged front view illustrating the riser legs in an assembled position, the rear view being a mirror image thereof;

FIG. 10 is an enlarged right side view illustrating the riser legs in an assembled position, the left side view being a mirror image thereof;

FIG. 11 is an enlarged top view illustrating the riser legs in an assembled position; and,

FIG. 12 is an enlarged bottom view illustrating the riser legs in an assembled position.
